PARTITION

Tai Y. Kim, Chicago, Ill., assignor to Container Corporation of America, Chicago, Ill., a corporation of Delaware

Filed Aug. 9, 1965, Ser. No. 478,255
12 Claims. (Cl. 229—15)

This invention relates to a partition formed of foldable paperboard, and more particularly, to a partition having a base pad and separator panels hinged to and upstanding from the base pad for defining four horizontally spaced areas.

An object of this invention is to provide a paperboard partition having a base pad of full transverse partition dimension and having two full height separator sections upstanding from the base pad and meeting medially thereof to define four spaced areas on the base pad.

Another object of this invention is to define a partition of the type noted in the previous object that is unusually stable and rigid when erected but yet that requires a near minimum amount of paperboard.

These and other objects will be more fully appreciated after reviewing the following specification including the accompanying drawings, wherein:

FIG. 1 is a perspective view of a first embodiment of the subject partition;

FIG. 2 is a plan view of a blank suitably cut and scored to form the partition of FIG. 1;

FIGS. 3 and 4 are perspective and plan views, respectively, of the partition of FIG. 1 shown in various stages of assembly;

FIG. 5 is a perspective view of a second embodiment of the subject partition;

FIG. 6 is a plan view of a blank suitably cut and scored to form the partition of FIG. 5; and

FIG. 7 is a perspective view of the partition of FIG. 5 shown partially set up.

Two embodiments of the subject partition are shown in FIGS. 1 and 5. Each of the embodiments includes a base pad 10 and two vertically upstanding sections 12 and 14 which meet approximately centrally of the base pad to divide it into four areas. Edge panels extend upwardly from the base pad 10 along diametrically opposite side edges thereof, and are generally equal in size and extend parallel to the separator section 12. The edge panels are hinged to the base pad 10 and to the separator section 14. In the embodiment disclosed in FIG. 1, the edge panels and separator section 12 extend transversely to the longer dimension of the base pad; whereas in FIG. 5, the edge panels and separator panel 12 extend longitudinally of the longer dimension of the base pad.

Referring now to FIGS. 2, 3, and 4 for a detailed description of the partition of FIG. 1, blank 20 is seen to be divided by two generally parallel spaced lines 22 into a middle section and two spaced end sections. The endward portions of each line 22 are scored as at 24 to define hinge areas between the middle and end sections, and the middle of each line is uninterruptedly cut as at 26 between and to the scored areas 24 to separate the middle and end sections. The middle section between the spaced lines 22 defines the base pad 10, and is divided by an uninterrupted cut as at 28 extending normal to and connecting the cuts 26 at lines 22 to define two base panels 30 and 31.

The end sections are each divided by parallel spaced lines 32 which are scored as at 33, and which extend only between the blank edges and lines 22 normal to the lines. The lines 32 are located approximately one-quarter way in from the adjacent blank edges to divide the end sections into two end panels 34 and 36 of equal size and a middle panel 38 twice as large as the end panels. Each

2

juncture between base and end panels is further provided with a slot 40 extending outwardly from the scored area 33 and of width approximately equal to, but slightly in excess of the thickness of the paperboard blank.

5 The partition is set up by initially folding the end sections about hinge areas 24 upwardly approximately 90° from the middle section. Thereafter, the base panels 30 and 31, which are originally coplanar and parallel to one another, are deflected slightly vertically at the edges adjacent cut 28 in the opposite directions to provide that the panels can overlap one another (as shown in FIG. 3 or 4), and are then swung in opposite directions until the edge of base panel 31 abuts the hinged juncture 24 between the base and end panels. Panel 31 is then fitted 10 through slot 40 and base panels 30 are moved away from one another in line generally with the free edge defined by the cut 28 to slightly deflect the portions 42 of end panels 34 and 36 over slots 40 to permit the base panels to clear one another and become coplanar once again.

15 In the setup condition, base panels 30 and 31 are substantially coplanar and parallel to one another and the two separator sections substantially divide the base pad into four horizontally separated sections. Similarly, the 20 separator sections extend perpendicular to one another and the one separator section 14 extends entirely across the base pad between the opposite edge panels. The partition can be torn down or disassembled by reversing the 25 procedure noted above.

The embodiment disclosed in FIGS. 5, 6, and 7 differs 30 from that previously disclosed in the manner in which it is formed. In this embodiment, base pad 10 is comprised of two separate base panels 52 and 54, and each separator section 12 and 14 is comprised of a single panel 56 and 58, respectively.

35 To form the partition, rectangular blank 60 is divided by a first pair of spaced parallel lines 62 and 64, and by a second pair of spaced parallel lines 66 and 68 which extend normal to the first pair of lines and which trisect the blank. Line 62 of the first pair of lines extends entirely 40 across the blank and includes at its opposite ends outwardly of lines 66 and 68, spaced score areas 70 and 72, and which includes to and between the lines 66 a cut area 74. The second line 64 extends only two-thirds across the blank and includes a cut area 76 between lines 66 and 68, 45 and a scored area 78 extending from line 68 to the adjacent blank edge. Line 66 of the second pair extends only outwardly of the first pair of lines, and includes a cut area 82 between and to cut 76 and the adjacent blank edge, and a scored area 84 between cut area 74 and the adjacent blank edge. Line 68 includes a cut area 86 extending between and to cut areas 74 and 76 and a scored area 88 extending between the cut area 74 and the adjacent blank edge. As such, the blank is divided into the base panels 52 and 54, the separator section panels 56 and 58, and edge panels 90 and 92.

50 The partition is formed by initially lifting the edge panel 92, base panel 54, and separator section panel 56 upwardly relative to the remaining base panel 52 and edge panel 90, with the separator section panel 58 accommodating this movement by means of its hinged connections 84 and 88 to the edge panels. Thereafter, the separator section panel 56 and base panel 54 are folded in the same direction about their hinged connections 78 and 72, and the edge panel 90 is folded about its hinged connection 70.

55 The separator section panels 56 and 58 have notches 96 each open to the edge of the panel to receive one another (as shown in FIG. 7) for interfitting the panels together.

In the set-up condition, the base panels 52 and 54 are 60 coplanar with one another and the separator section panels 56 and 58 cross one over the base panels. The line 64 of the blank is located about one-sixth the length of the

blank from the adjacent blank edge, and the lines 62 and 64 are spaced from one another the same one-sixth distance in the preferred embodiment.

While two specific embodiments of the subject invention have been disclosed, it will be obvious to those skilled in the art that modifications can be made therefrom without departing from the inventive disclosure. Accordingly, it is desired that the subject invention be limited only by the scope of the claims hereinafter following.

I claim:

1. A partition formed from a generally rectangular paperboard blank suitably cut and scored to comprise the combination of:

- (a) a rectangular base pad of smaller area than the area of the blank and including first and second substantially coplanar, aligned base panels that together define the horizontal dimensions of the partition; 15
- (b) first and second edge panels upstanding vertically from diametrically opposite side edges of the base pad and being hinged at their lower edges respectively, to the first and second base panels and extending only a fractional part of the length of the base pad; 20
- (c) separator sections upstanding vertically from the base pad and extending at right angles to one another to divide the base pad into four horizontally separated areas; 25
- (d) one of the separator sections being hinged at the outboard ends thereof to corresponding inboard ends of the edge panels, respectively, and extending entirely across the base pad completely separated therefrom; 30
- (e) the other separator section being hinged at least along part of its lower edge to the base pad and extending entirely across the base pad substantially parallel to the edge panels; 35
- (f) the vertical heights from the base pad of the edge panels and the separator sections being equal and defining the vertical dimension of the partition.

2. A partition according to claim 1, wherein each separator section includes a pair of panels each extending only part way across the base pad, and wherein the panels of said other separator section are hinged, respectively, to the base panels along the side edges thereof directly opposite the hinged connection of the edge panels. 40

3. A partition according to claim 2, wherein at least the first edge panels are separated from the first base panels in the region closely adjacent the hinged connection thereof to the separator section panels by slots of width equal approximately to the thickness of the blank. 45

4. A partition according to claim 1, wherein each separator section includes only a single panel extending continuously across the base pad, and wherein the panel of said other separator section is hinged at its lower edge along only a fractional part of its length to the first base panel at the inboard edge thereof and is completely separated along the remainder of its length from the second base panel. 50

5. A partition according to claim 4, wherein the separator section panels are notched medially thereof at their adjacent edges to interfit with one another at their intersection. 60

6. A blank of foldable paperboard suitably cut and scored for forming a partition having a base pad and having separator sections upstanding vertically from the base pad for defining four horizontally separated areas, the combination comprising:

- (a) a first pair of spaced parallel lines extending across the blank and a second pair of spaced parallel lines extending partly across the blank normal to the first pair of lines; 70
- (b) said second pair of lines being spaced from the adjacent blank edges distances each corresponding to one-quarter the blank length in the direction parallel to the first pair of lines, and the first pair

of lines being spaced apart a distance corresponding to one-half said blank length symmetrically of the adjacent blank edges;

- (c) each of said first pair of lines including spaced hinged areas between the second pair of lines and the adjacent blank edges and a cut area through the blank extending uninterruptedly between and to said second pair of lines;
- (d) each of said second pair of lines extending only between the first pair of lines and the adjacent blank edges and being hinge areas;
- (e) a cut area through the blank extending normal to and uninterruptedly between the first pair of lines midway between the second pair of lines;
- (f) the partition being set-up initially by folding the blank at the hinge areas of the first pair of lines approximately 90° and thereafter substantially simultaneously folding the blank at the hinge areas of the second pair of lines approximately 90°, the latter folding step following the slight displacing of the blank edges adjacent the midway cut area in order to permit the aligned edges to clear one another, and the direction of folding on each line of the respective pairs of lines being the same about said line but the direction of folding on the lines of each pair of lines being opposite to one another.

7. A blank according to claim 6, wherein the first pair of lines further includes slots cut in the blank at the hinge areas extending from at least one of the second pair of lines only part way to the adjacent edge of the blank, the slots being approximately as wide as the thickness of the blank.

8. A blank of foldable paperboard suitably cut and scored for forming a partition having a base pad and having separator sections upstanding vertically from the base pad for defining four horizontally separated areas, the combination comprising:

- (a) a first pair of spaced parallel lines extending partly across the blank and a second pair of spaced parallel line extending partly across the blank normal to the first pair of lines and trisecting the blank in that direction;
- (b) one line of the first pair of lines being spaced from the adjacent blank edge and said first pair of lines being spaced apart distances each corresponding to one half the distance between said second pair of lines;
- (c) said one first pair line extending only between one line of the second pair of lines and the blank edge adjacent the other line of the second pair of lines, and including a cut area through the blank extending uninterruptedly between and to said second pair of lines and a hinge area extending between said other second pair line and the adjacent blank edge;
- (d) the other line of said first pair of lines including spaced hinge areas between said second pair of lines and the adjacent blank edges and a cut area through the blank extending uninterruptedly between and to said second pair of lines;
- (e) said one second pair line extending only between the first pair of lines and the blank edges, and including a cut area through the blank extending uninterruptedly between and to said one first pair line and the adjacent blank edge;
- (f) said other second pair line extending only between said one first pair line and the blank edge adjacent said other first pair line, and including a cut area through the blank extending uninterruptedly between and to the first pair of lines and a hinge area extending between the other first pair line and the adjacent blank edge;
- (g) the partition being set up by initially folding the blank at the hinge areas of the second pair of lines

each approximately 90° in the opposite direction, and thereafter substantially simultaneously folding the blank at the hinge areas of the first pair of lines approximately 90° all in the same direction so that two panels form the base pad and two panels form the separator sections and cross one another approximately centrally of the base pad.

9. A blank according to claim 8, wherein said crossing separator section panels have a pair of edge notches parallel to the second pair of lines to provide for an inflection of the panels when they are crossed.

10. A partition formed from a paperboard blank suitably cut and scored to comprise the combination of:

- (a) a base pad including first and second substantially coplanar, aligned base panels;
- (b) first and second edge panels upstanding from diametrically opposite side edges of the base pad and being hinged at their lower edges respectively, to the first and second base panels and extending only a fractional part of the length of the base pad;
- (c) separator sections upstanding from the base pad and extending transversely to one another to divide the base pad into four separated areas;
- (d) one of the separator sections being hinged at the outboard ends thereof to corresponding inboard ends of the edge panels, respectively, and extending across the base pad completely separated therefrom;
- (e) the other separator section being hinged at least along part of its lower edge to the base pad and extending across the base pad between the edge panels.

11. A blank of foldable paperboard suitably cut and scored for forming a partition having a base pad and having separator sections upstanding from the base pad for defining four separated areas, the combination comprising:

- (a) a first pair of spaced lines extending across the blank and a second pair of spaced lines extending partly across the blank transversely to the first pair of lines;
- (b) said second pair of lines being spaced apart a distance at least as great as the space between the first pair of lines, and the first pair of lines being disposed generally symmetrically of the adjacent blank edges;
- (c) each of said first pair of lines including spaced hinged areas between the second pair of lines and the adjacent blank edges and a cut area through the blank extending uninterruptedly between and to said second pair of lines;
- (d) each of said second pair of lines including hinge areas between the first pair of lines and the adjacent blank edges;
- (e) a cut area through the blank extending transversely to and uninterruptedly between the first pair of lines between the second pair of lines;
- (f) the partition being set-up initially by folding the blank at the hinge areas of the first pair of lines and thereafter substantially simultaneously folding the

blank at the hinge areas of the second pair of lines, the direction of folding on each line of the respective pairs of lines being the same about said line but the direction of folding on the lines of each pair of lines being opposite to one another.

12. A blank of foldable paperboard suitably cut and scored for forming a partition having a base pad and having separator sections upstanding from the base pad for defining four separated areas, the combination comprising:

- (a) a first pair of spaced lines extending partly across the blank and a second pair of spaced lines extending partly across the blank transverse to the first pair of lines;
- (b) the second pair of lines being spaced apart a distance greater than the spacing of said first pair of lines but no greater than one-half the longer blank length;
- (c) one line of said first pair of lines including a cut area through the blank extending uninterruptedly between and to said second pair of lines and a hinge area extending between one line of said second pair of lines and the adjacent blank edge;
- (d) the other line of said first pair of lines including spaced hinge areas between said second pair of lines and the adjacent blank edges and a cut area through the blank extending uninterruptedly between and to said second pair of lines;
- (e) said one second pair line including a cut area through the blank extending uninterruptedly between and to the first pair of lines and a hinge area extending between the other first pair line and the adjacent blank edge;
- (f) the other said second pair of lines including a cut area through the blank extending uninterruptedly between and to said one first pair line and the adjacent blank edge and a hinge area between said other first pair line and the adjacent blank edge;
- (g) the partition being set up initially folding the blank at the hinge areas of the second pair of lines in opposite directions, and thereafter substantially simultaneously folding the blank at the hinge areas of the first pair of lines all in the same direction so that two panels form the base pad and two panels form the separator sections and cross one another over the base pad.
